UNITED STATES PATENT OFFICE.

ALPHONS DRYFOOS, OF NEW YORK, N. Y.

DESIGN FOR A BOTTLE.

SPECIFICATION forming part of Design No. 23,240, dated May 1, 1894.

Application filed March 6, 1894. Serial No. 502,589. Term of patent 7 years.

To all whom it may concern:

Be it known that I, ALPHONS DRYFOOS, of the city, county, and State of New York, have invented a new and original Design for a Bottle, of which the following is a full, clear, and exact description.

Reference is to be had to the accompanying drawings forming a part of this specification, in which similar letters of reference indicate corresponding parts in both the figures.

Figure 1 is a perspective view of a bottle showing the design; and Fig. 2 is a sectional plan view of the same.

The leading feature of my design consists

in the bottle having the two sides A, B, disposed in vertical planes.

A minor feature of the design is the cross section of the bottle being approximately triangular with the side D forming a segment of a circle the center of which is in the intersection line C of the sides A, B.

I claim—

The design for a bottle, as herein shown and described.

ALPHONS DRYFOOS.
